United States Patent Office.

T. C. COLEMAN, OF LOUISVILLE, KENTUCKY.

Letters Patent No. 86,004, dated January 19, 1869.

IMPROVEMENT IN THE MANUFACTURE OF WROUGHT-IRON.

The Schedule referred to in these Letters Patent and making part of the same.

To all whom it may concern:

Be it known that I, T. C. COLEMAN, of Louisville, in the county of Jefferson, and State of Kentucky, have invented a new and improved Manufacture of Wrought-Iron; and I do hereby declare that the following is a full, clear, and exact description thereof, which will enable others skilled in the art to make and use the same.

This invention relates to an improved process for the manufacture of iron; and consists in the manner of mixing and combining iron-cinders or other flux, with molten pig-metal, previously to working it into puddle-balls.

I melt pig-iron and iron-cinders, or other flux, in proper proportions, in a cupola or furnace previous to the admission of the same to the puddling or reverberatory furnace, by adding the cinder or other flux after the pig-metal has been melted. I then tap the cupola and admit the compound into the said puddling-furnace, where the stirring and boiling-operation

is carried on in the old and well-known manner, and more cinder or other flux may be added at the time of tapping into the puddling-furnace.

I have found, in practice, that this method admits of a better fluxing of the substance than can be effected when all the mixing is effected in the reverberatory furnace, under the action of the air therein, which is the common method, as now practised, of fluxing with iron-cinder, or other flux, stirring and balling.

Having thus described my invention,

I claim as new, and desire to secure by Letters Patent—

Mixing iron-cinder or other flux with pig-metal, in the cupola or furnace, previous to and at the time of transferring it to the reverberatory furnace, substantially as and for the purpose specified.

T. C. COLEMAN.
